UNITED STATES PATENT OFFICE

WILLIAM BAYLEY, OF SPRINGFIELD, OHIO

ROAD-BUILDING APPARATUS

Application filed May 11, 1925. Serial No. 29,514.

My invention relates to road making apparatus and more particularly to an automatic machine for compacting and finishing concrete roadways of predetermined grades and contours.

In the present invention there are contemplated two automotive carriages traveling upon the side forms of the concrete road-bed to be built, as guide tracks, and carrying between them an adjustable vibratory beam or shoe arranged transversely of the road-bed, which as the apparatus advances tamps and compacts the plastic concrete with a combined downwardly and forwardly directed stroke, which strikes off the surplus material to predetermined grade and contour, settling and driving downward the coarse material and bringing to the surface the finer materials to afford a smooth impervious surface. The traveling carriages are yieldingly connected one to the other enabling the machine to spread and contract automatically as the width of the road varies and to compensate for irregularities in the setting of the side forms. The vibratory tamping means or shoe is further adjustable to vary the transverse contour or crown of the road while in operation, enabling the road surface to be progressively flattened as the machine approaches a curve, and the crown again raised as the machine passes beyond the curve. The carriages are provided with compensating driving mechanism to enable the negotiation of curves of various radii. At the end of the tamping device are carried spading plates, which operate in close proximity to the side forms to displace inwardly the coarse material, leaving smoothly finished side surfaces. These plates penetrate the paving bed and prevent spilling over the forms.

The operation of the machine performs a new method or process of compacting concrete involving something more than mere tamping and produces results not attainable by hand operations.

The vibratory tamping shoe or beam is inclined upwardly and forwardly, the under surface being flat, concave or convex as may be required by the conditions of use and character of materials operated upon. This

shoe or beam presents in relation with the road bed, a converging mouth in which an excess of material collects as the machine advances. The camming action of the inclined shoe in addition to its vibratory movement exerts a squeezing effect upon the mass of material beneath the shoe, which gradually increases as the machine advances, thus bringing the small particles of sand and gravel closer together and ejecting forwardly the liquid cement and water. In the event a surplus amount of sand and gravel accumulates, such portion as can not be compressed below the grade line is progressively squeezed forwardly, intermixed with the expressed cement and water into a more or less fluid state. The effect of the process is to bring the sand and gravel, or sand and broken stone, if the latter be used, into close and intimate contact with only enough cement between to effect the union or adhesion of the particles. It has been found by experiment and practice, that an excess of cement is detrimental and affords a less durable and less strong body. A thick bond of cement is not in itself sufficiently resistant and does not possess the requisite tensile or compressive strength. When such thick bond is broken, it allows relative grinding movement or inter-attrition of the stone, gravel and sand. By closely compacting the materials by the present method whereby the sand and gravel or stone is separated by only a thin film of cement, a better union is effected and the particles being densely associated are intersupporting and the cement bonding is not subjected to the strain and stress as when the particles are more widely separated and the cement bondings thicker. The agitation of the surplus material squeezed forwardly at each operation of the shoe and the ejection of the liquid cement through the surplus material making the mixture more fluid insures a uniform mixture and the thorough coating of every particle with liquid cement. The machine thus to a limited degree supplements the action of the concrete mixer by insuring uniformity of the mixture as it is incorporated in the deposited stratum. By the

progressive squeezing and compacting operations, the excess moisture is removed from the concrete deposit as the machine advances, leaving the completed body dense, hard and comparatively dry, and in a condition to set more quickly. This mode of operation, not only affords stronger concrete, but saves cement and time. The saving of cement by this method which insures a thin but uniform coating of the aggregates, not only insures better built roads, but also cheaper roads.

While the tamping or ramming action of the shoe is advantageous in effecting a dense compact deposit, the machine can be successfully operated without the vibration of the shoe. By holding the shoe down and advancing the machine onto the soft mixture, the upturned face of the shoe forms a converging throat which as the machine advances affords a camming action which forces the material down below the grade level, squeezing the loose material into a dense solid stratum from which the moisture and liquid cement is expressed and simultaneously striking off the surface with a smoothing or troweling effect. The top stratum of the finished road way will be substantially the same as when tamped, but the dense superstratum will not be so deep, and the coarse materials not so deeply submerged as when the mass is tamped by the vibratory movement of the shoe.

The final action of the trailing edge of the shoe is to wipe the compressed surface with a troweling effect to which end the under surface of the shoe is provided with a final substantially flat surface. For best result, this surface is not exactly level, but is given a small clearance or elevation at its forward edge, so that a final squeezing and smoothing effect is afforded.

The object of the invention is to simplify the structure as well as the means and mode of operation of road building apparatus, whereby such machines will not only be cheapened in construction, but will be more efficient in use, uniform in operation, automatic in action, easily controlled and unlikely to get out of repair.

A further object of the invention is to provide a tamping movement, which not only exerts downward pressure, compacting the material and submerging the coarse aggregates, but which at the completion of its downward stroke will affect a forward smoothing movement, striking off and advancing the surplus material and leaving a smooth uniform finished surface.

A further object of the invention is to provide means for varying the transverse contour of the finished surface, enabling the surface to be finished flat or crowned to varying degree as may be required.

A further object of the invention is to

provide a floating frame construction, enabling the machine to expand and contract to accommodate variations in the width of the road-way and inequalities in the setting of the side forms. This feature of adjustability is further designed to enable the machine to be employed as a unit of reduced size for constructing concrete roads under traffic, wherein only one lateral half of the road is paved, while traffic is directed over the unpaved half and thereafter the remaining lateral half of the road paving is completed while traffic is using the initially paved portion. While the apparatus is designed primarily for operating the full width of the roadway, it is so constructed that it may be contracted to any desired lesser width unit, without interference with the operating or driving mechanism.

A further object of the invention is to provide an improved driving mechanism for apparatus of the present character, whereby the carrying wheels at the opposite sides of the machine are differentially propelled, enabling the apparatus to accommodate itself to curvatures of the roadway without slippage and without distortion or straining of the apparatus, and to further provide transmission mechanism for actuating the machine forwardly and rearwardly as may be found necessary.

A further object of the invention is to provide improved spading means for finishing the lateral margins of the roadway and at the same time confining the material on the sides and preventing slipping over the forms, compacting the margin and submerging the coarse materials to not only afford a more pleasing and finished appearance, but strengthening the margins of the paving to prevent crumbling.

With the above primary and other incidental objects in view as will more fully appear in the specification, the invention consists of the features of construction, the parts and combinations thereof, and the mode of operation or their equivalents as hereinafter described and set forth in the claims.

In the accompanying drawings, wherein is shown the preferred, but obviously not necessarily the only form of embodiment of the invention, Fig. 1 is a top plan view of the assembled machine, illustrating the relative location of the various parts. Fig. 2 is an end elevation. Fig. 3 is an enlarged plan view of one end of the assembled machine, illustrating the several driving trains of mechanism. Fig. 4 is a rear elevation, of the right hand carriage with the side frame in section just back of the shoe, wherein the tamping means is shown aligned throughout to produce a flat surface. Fig. 5 is a similar view showing the tamping beam or shoe only, and adjusted to provide a crowned surface.

Fig. 6 is a detail view of a tamping beam or surfacing shoe only, comprising a single continuous section, extending from one side of the road surface to the other, and contoured for producing an arcuate crowned surface. Figs. 7 and 8 are detail transverse sectional views illustrating the beam adjusting means, by which it is medially raised and lowered to vary the crown or transverse contour of the finished surface. Fig. 9 is a detail sectional view of the yielding central joint, between the inner ends of the tamping bar or shoe sections. Fig. 10 is a diagrammatic view illustrating the path of travel of the heel point of the tamping beam or shoe, throughout successive strokes. Fig. 11 is a detail rear elevation of the gear transmission devices. Fig. 11^a is a detail side elevation of the gear transmission looking with arrows 20 Z on Fig. 3. Fig. 12 is a detail sectional view of the telescopic main frame. Figs 13 and 13^a, 13^b and 13^c illustrate a modification of the tamping beam actuating mechanism. Fig. 14 is two diagrammatic illustrations of the tamping beam movement at its heel under control of the mechanism shown in Fig. 13 and 13^a. Fig. 15 is a rear elevation of the two carriages of the machine in distended relation, and carrying a 25 one piece rigid beam having its lower side arcuate. The carrying wheels are omitted to avoid complication. Fig. 15^a is an end view of the beam shown in Fig. 15, showing the end plate and the spader plate, the latter in lowered position. Fig. 15^b is a view 30 similar to 15^a illustrating a differently mounted spader plate. Fig. 16 is a view similar to Fig. 15 but with the two carriages telescoped as closely together as possible, and with the rigid beam shaped on the under 35 side for finishing a road of conic section. Fig. 17 is similar to Fig. 16, it shows, however, the carrying wheels, and shows a rigid beam notched off at one end and a temporary form laid inside of one edge of the paving bed in order to surface a more narrow roadway than the machine is contemplated for. Fig. 17^a is an end view of the structure shown 40 in Fig. 17. Fig. 18 is similar to Fig. 15 except that it shows the machine narrowed and the beam shaped for a conic sectioned road. Fig. 19^a is similar to Fig. 16, but with the machine narrowed. Fig. 19 is a rear view of the machine without the telescopic arrangement, both carriages being secured rigidly 45 to a one piece frame member. It shows the beam notched off on one end, and arranged for a narrower roadway than the capacity of the machine. Fig. 20 is a sectional view 50 showing the vibrating shoe preceded by an optionally usable series of agitating fingers and an adjustable strike plate. Fig. 21 is a partial front view of the agitating fingers and strike plate shown in Fig. 20. Fig. 22 55 shows a modification of the vibrating shoe

and its operating mechanism: it also shows a flexible slicker attached to the vibrating shoe. Fig. 23 shows two partial front views of a strike plate and of agitating fingers optionally and adjustably usable in connection with the shoe. Fig. 24 is a diagrammatical illustration of the shoveling movement of the point of the fingers or plate shown in Fig. 22 and Fig. 23, when the machine is moving forward. Fig. 25 is a diagrammatical illustration of the movement of the rear end of the flexible slicker plate, shown in Fig. 22, when the machine is moving forward. Fig. 26 is a diagrammatical illustration of the movement of the rear end of the flexible slicker plate shown on Fig. 22 when the machine is moving backward and the movement of the shoe is the same as when the machine is moving forward.

Like parts are indicated by similar characters of reference throughout the several views.

The present apparatus is designed to travel under its own power in bridging relation across the surface of the roadway to be finished and employing the side forms, containing the concrete deposit, as guide tracks. While the ordinary wooden form boards commonly employed to define the lateral margin of the roadway and to confine the deposit of concrete in a semi-fluid or plastic stage, if sufficiently strong and well braced, may be employed for such guide track purposes, for economy as well as ease of operation, there are preferably employed metal flanged side forms, 1-1, which serve the double purpose of guide tracks and concrete form sides. These side rails or forms 1, are provided with base flanges projecting outwardly therefrom and resting upon the road-bed and also with out-turned angle flanges 3, which form the track for the carrying wheels of the machine. The concrete material is deposited intermediate the side rails or forms 1-1, from the usual mixer. The quantity so deposited is slightly in excess of the maximum requirement to fill the form to the desired and established grade. The present machine traveling upon the side rails or form sides 1-1 follows the concrete mixer and while the material is yet in a semi-fluid or plastic stage it progressively advances over the deposit of concrete tamping and compacting the material to uniform grade and contour, striking off the surplus material and leaving the surface smoothly finished.

The main frame of the apparatus consists of two traveling carriages 4 and 5, interconnected by pipe sections 6 and 7. One of the pipe sections 7 is telescopically arranged 125 within the pipe section 6, permitting thereby a limited range of movement of the traveling carriages 4 and 5 toward and from each other transversely of the road-bed. Each of the traveling carriages comprises a body por-

tion formed from spaced channel bars 8, interconnected in spaced relation by truss bars or by connecting plates from which extend dependent leg portions 9, to which are suitably journalled carrying wheels. The carriage 4 is provided with two double flanged carrying wheels 10 while the other carriage 5 has one double flanged wheel 10 and an unflanged wheel 10^a. The flanges 11 of the carrying wheels 10 are flared or tapered to enable the carrying wheels to more easily negotiate curved sections of the track rail or side forms 1. The innermost flange of the carrying wheels is of less thickness than the outer flange, thereby minimizing the disturbance of the material near the form. The forward and unflanged wheel 10^a of the carriage 5 is of wide face to allow the machine to negotiate curves and the two double flanged wheels of the carriage 4 guides the travel of the machine along the paving bed. Connected to the primary or propelling carriage 4 are two standards or pipe sections 6, connected end to end, and having interposed therebetween, the head or supporting plate 12, provided with bearings for the operating shafts. Corresponding plates 13 are provided at the opposite ends of the respective pipe sections 6 and fixedly secured thereto. The pipe sections 6 may be varied in length and diameter in accordance with the span of the apparatus. However, for roads of the usual width, standard nine inch pipe sections have been found quite suitable. Such sections are used for economy of construction and to afford the necessary rigidity and strength to resist the strains, torsion and tension to which the apparatus frame is subjected in operation. It will be understood, however, that in lieu of interconnecting sections of pipe, frame members of differently shaped cross area may be employed. Pipe sections are employed because of their great strength to resist torsion. All of the principal bearings for the machine are carried to pipe 6 and the back thrust of the shoe 21 must be resisted and transmitted to carriage 4 by the pipe 6. Connected to the second carriage 5 is a flanged pipe section 7, of less diameter arranged telescopically with in the section 6. The telescopic sections 6 and 7 are provided with anti-friction rollers 14 and 15, which facilitate the to and fro adjustment to compensate for variation in the spacing of the track rails or side forms 1. The antifriction roller 14, engages exteriorly of the telescopic pipe sections 7 through openings in the exterior pipe section 6. At the same time the second set of anti-friction rollers 15 located interiorly of the sliding pipe section 7 adjacent its inner extremity engage the interior of the pipe section 6 through suitable openings in the inner pipe 7.

Mounted in suitable adjustable bearings in the head plates 12 and 13, is a drag shaft 16, 65 on which are journalled for rocking move-

ment independent of the drag shaft, a plurality of downwardly and rearwardly extending drag bars 17. These drag bars are loose upon the drag shaft 16, but the latter is capable of limited rocking movement to effect the adjustment of the tamping shoe or beam as will be described. The bearing of the shaft 16 can be adjusted up and down to vary the angle of the working face of the beam 21.

At their rearward and lower ends the drag bars 17 are connected by links 18 with rock arms 19 upon a rock shaft 20, mounted in suitable bearings in the head plates 12 and 13. The link 18 and arm 19 comprise in effect a toggle joint connection, which under the rocking movement of the shaft 20 vibrates the drag bars, actuating such bars in their downwardly and forwardly stroke with great pressure. For simplicity and economy of manufacture, the drag bars 17, each comprise a pair of angle bars arranged in spaced relation, interconnected by transverse bolts with intermediate spacers. In the drawing three of such drag bars or pairs of angle bars have been shown.

Suspended beneath the oscillatory drag bars 17 is the tamping beam or shoe 21, formed in two angularly adjustable sections, connected by an adjustable joint 22. This joint is of concavo-convex form, wherein one of the sections is somewhat reduced at its extremity and fits within a recess or groove formed by marginal flanges 23 on the opposing member, the two sections being held together by tie bolts 24 carrying helical compression springs 25, against the yielding resistance of which the sections of the beam 21 are adjustable to a limited angular relation with each other. Projecting shield plates 26 carried by one of the beam sections and overlapping the joint, serve to close the marginal opening between the beam section when angularly adjusted. The lip or flange 23 on the lower side of the tamping beam maintains close engagement in the rabbet of the opposing beam section, where it is held under the tension of the spring 26 in all positions of adjustment of the beam section. This method of connecting the two sections of the beam 21 together affords a tight joint on the bottom and also allows the outside section next to carriage 5 to be easily disconnected by removing the bolts 24 and spring 25, in which case this section comes away from the other along with the outside lengths of pipe 6 and shafts 16 and 20, which have been provided with couplings 16^a and 20^a for this purpose. The beam sections 21 are provided with vertically disposed hanger plates. These hanger plates extend intermediate the angle bars forming the drag bars 17. The plates 27 at the opposite ends of the tamping beam and pertaining to the terminal drag links 17 are suspended on transverse studs 28, mounted in the parallel angle bars forming the drag link and extending through cor-

responding holes in the suspension plate 27, which holes are sufficiently large to permit the necessary play and compensating movement to accommodate the elevation of the medial joint 22 of the beam. Each of the drag links 17 is provided with a pair of angle plates 29, secured to the drag link and overlapping the tamping beam or shoe 21 and serving as thrust bearings for the shoe or beam. In the drawings, the rearmost thrust plate 29 is shown operating in a slot 30 in the shoe or beam, while the forward thrust plate overlaps the forward marginal edge of the beam or shoe 21. This beam or shoe is inclined upwardly and forwardly with the forward margins elevated a considerable distance above the road-bed, while the heel of the shoe or beam is finished with a smoothing surface 31, substantially horizontally disposed, and parallel with the finished surface of the roadway. The hanger plate pertaining to the middle drag link 17 differs somewhat in its mounting from those at the ends of the beam. Instead of being suspended directly from the drag link 17 as are the terminal hanger plates 27, the medial plate 27^a is suspended from two rock arms or bell crank levers 32 and 33. The bell crank lever 32 is keyed or otherwise fixedly mounted upon the drag shaft 16. The second bell crank lever 33 is pivotally mounted upon a transverse stud 34 carried by the drag link 17. The hanger plate 27^a has slotted connections 35 with the rock arms of the bell crank levers 32 and 33, so that as these bell crank levers are oscillated, the hanger plate 27^a and with it the tamping beam or shoe section 21, are raised and lowered. The bell crank levers 32 and 33 are caused to oscillate in unison by an intermediate connecting link 36, which transmits the rocking movement of the drag shaft 16 to the rearward elevating crank lever 33. The drag shaft 16 is manually rocked by means of a lever 38, secured to the shaft 16 and engageable with the usual notched segment 39, in various positions of oscillatory adjustment. This notched segment 39 is secured to one pair of drag links 17 and oscillates with them. The lever 26 can be operated as the machine is being propelled along the roadway, one notch in a given distance. It is possible to do this adjusting automatically however. A simple way is shown in the drawings. By the to and fro adjustment of the hand lever 38, the drag shaft 16 is rocked to in turn raise and lower the medial portion of the tamping beam or shoe 21 by flexing the joint 22 thereby varying the crown of the finished road surface and its lateral inclination. By this adjustment the respective sections of the tamping beam or shoe 21 may be aligned throughout to produce a transversely level or uniform finished surface as shown in Fig. 4, or the center of the beam or

shoe may be elevated to various altitudes producing the transversely crowned or laterally inclined surface shown in Fig. 5, and this can be done while the machine is in action. The finished surface is produced in either flat or variously contoured crowned form, by striking off the surplus material and compressing the remaining body of concrete by repeated downward and forward thrusts of the beam or shoe 21, effected by the rocking movement of the shaft 20 which is transmitted through the toggle connections 18 and 19 to the vibrating drag bars 17.

For economy of manufacture and convenience of control, the power transmission feature by which the shaft 20 is given a rocking movement and the apparatus as a whole propelled forwardly or rearwardly as may be required, are concentrated upon and adjacent to the primary carriage 4. On this traveling carriage 4 is located a suitable engine or motor 40, preferably of the explosive type, but which may be of any suitable and convenient character. This engine or motor 40 is connected by a chain belt with a drive sprocket 41 upon a power shaft 42, mounted in suitable bearings upon the carriage 4. The power shaft 42 carries intermediate the bearing brackets 43, a pair of interconnected sliding gear pinions 44. The gears 44 having driving engagement with the shaft 42 are slideable thereon by the shift lever 45 into and out of mesh with two gears 46—46, journaled upon the bearing brackets 43 and interconnected eccentrically by a wrist pin 47, on which is journaled the connecting rod or pitman 48. This connecting rod or pitman 48 is pivoted at its opposite end to a rock arm 49, upon the rock shaft 20. The rotation of the power shaft 42 driven by the engine 40 is transformed by the crank and pitman connection with the gears 46 into rocking movement transmitted to the shaft 20 by which the drag link 17 and tamping beam or shoe section 21 are given a rising and falling movement as the machine progresses. These parts are operatively connected and disconnected by the shifting movement of the driving gear pinions 44, controlled by the shift lever 45.

Mounted upon the power shaft 42 beside the sprocket wheel 41 is another sliding gear pinion 50, slideable into and out of driving engagement with an idler gear 52 to which is connected a second gear pinion 53, meshing with a gear 54, upon a power transmission shaft 55 extending in alignment with, but disconnected from the power shaft 42, or, into and out of engagement with the face of the gear 54. Connection through gear 54 gives fast speed and connection through gear 52 affords slow speed. By operation of the shift lever 45, the gear pinion 50 keyed upon the power shaft 42 is slidably adjusted into and out of mesh with the gear 52, and clutch en-

gagement with gear 54, thereby establishing driving connection between the power shaft 42 and transmission shaft 55. In an intermediate or central position of the shift lever, 5 the shafts 42 and 55 are disconnected. The transmission shaft 55 is mounted in a suitable bracket 56 upon a frame of the apparatus. It carries a pair of interconnected sliding gear pinions 58, controlled by a shift lever 59. 10 The shift levers 45 and 59 are operated from the side of the machine by reciprocating operating rods 60 and 61, having at their extremities, handles by which the rods are reciprocated to shift the respective gears into 15 and out of driving engagement, and are locked in position by slots in plate 43. The sliding gear pinion 58 constitutes the reversing and neutral means. When shifted toward the right in Fig. 1 and Fig. 3, one of the 20 gear pinions 58 is intermeshed with a spur gear 62, upon a counter shaft 63. When shifted in the opposite directions, the other driving gear pinion 58 is caused to intermesh with an idler 64 meshing with a gear 65 cor- 25 responding to the gear 62 and mounted upon the same countershaft 63, but serving to drive such counter shaft 63 in the opposite direction. The counter shaft 63 carries intermediate the gears 62 and 65, a gear pinion 66, 30 which intermeshes with the primary driving gear 67, of a differential or compensating gear train, contained within the differential housing 68. This differential or compensating gear train may be of any ordinary 35 construction, such as the compensating or differential gear mechanism of a motor vehicle, but of course of proportionate size and strength to the work to be performed. This differential mechanism serves to drive the 40 shaft 70 and shaft 71 extending in opposite direction from the differential housing 68, in unison, but permits the oppositely disposed shaft 70 and 71 to rotate independently to compensate for the differential travel of the 45 carriages 4 and 5 when following a curved path of travel. The shafts 70 and 71 extend transversely of the machine and are provided with bearings in the head plates 12 and 13. Each of these shafts is provided with a stand- 50 ard flexible coupling 72, which compensates for any unalignment or distortion incident to twisting strains to which the frame of the apparatus may be subjected. These couplings 72 may be of any approved form. The 55 usual type being a heavy disc of rubber or rubberized fabric or a succession of thin metal laminations, bolted between opposite coupling heads, the connections of which with the intermediate flexible disc are offset to permit a limited amount of angular distortion. Furthermore, the bearings of these shafts as well as the drag shaft 16 and rock shaft 20, in the bearing heads 12 and 13 are 60 provided with universally mounted journal boxes, which likewise compensate for a lim- 65 ited amount of distortion of the machine frame. The shaft 71 is provided with a coupling 71^a for disengagement when shafts 16 and 20 are disconnected. The shafts 70 and 71 are provided at their extremities with gear pinions 73 intermeshing with gears 74, 70 mounted on sprocket shafts 75 carried by the respective traveling carriages 4 and 5. The shaft 75 of the traveling carriage 5 is elongated at 76 and has splined engagement with the driven gear 74. This permits the traveling carriage 5 to have floating movement toward and from the carriage 4 as the width of the roadway and the spacing of the track forms 1 vary, while maintaining driving engagement between the gear 74 and sprocket shaft 75, through the entire range of such lateral movement of the traveling carriage. During such lateral shifting movement of the carriage 5, permitted by the telescopic relation of the pipe section 7, within the pipe 6, the extension 76 of the sprocket shaft 75 has similar reciprocating movement through the gear 74, which maintains its driving engagement with the shaft extension through its 80 entire range of movement. The shaft 75 of each of the traveling carriages 4 and 5 carry a sprocket wheel 77 over which passes a chain belt 78 engaging driving sprockets 79 upon the carrying wheels 10 and 10^a. The sprocket chain 78 passes around idler sprockets 80 and 81 intermediate its engagement with the carrying wheel sprockets 79. By this means power is transmitted to the carrying wheels to propel the apparatus either forwardly or 90 rearwardly according to the position of the shift lever 59, and the intermeshing engagement of the gear pinions 58. When the shift lever 59 is operated toward the left in Figs. 1 and 3 to intermesh one of the gear pinions 95 58 with the idler gear 64, from which motion is transmitted through the gear 65, the machine is propelled forwardly. Upon reverse movement of the shift lever 59, by which the other gear pinion 58 is intermeshed with the gear 62, thereby driving the counter-shaft 63 in reverse direction, the mechanism is propelled rearwardly. When the lever 59 is in central position the machine 100 is in neutral. The operation of the shift lever 105 51 moving the gear pinion 50 into and out of mesh with the gear 52 and 54 or stopping midway, serves to drive the machine either fast or slow or arrest its travel when the shift lever 51 is in an intermediate or neutral position. By disconnecting the gear pinion 44 from the crank gears 46 by the operation of the shift lever 45 and leaving the shift levers 51 and 59 in operative position, the apparatus 110 may be moved under its own power from 115 place to place without the operation of the tamping beam or shoe. 120 The tamping beam or shoe 21 being inclined upwardly and forwardly, in angular relation with the plane of the finished sur- 125 130

face, accumulates beneath it a surplus of material as at 82, which as the shoe or tamping beam advances is crowded downward toward the plane of the finished surface by the camming action of the beam further assisted by the downward and forward thrust of the beam or shoe, which is effected under great pressure by the toggle connection with the rock shaft. By this means, the surplus material is crowded downward below the plane of the finished surface and the body of concrete is increasingly compacted under pressure. The action of the shoe or beam submerges the coarse aggregates, allowing the finer portions of the mixture to rise to the surface. In addition to the compression and compacting action due to the camming action of the shoe or bar, and to the ramming incident to the repeated downward thrust movement of the bar or shoe, the body of concrete operated upon is subjected to a further smoothing or final wiping action in a forward direction at the completion of the thrust movement, because of the slow movement of the toggle joint when on the dead center, thus giving in effect a smooth troweled finish. The path of travel of the heel of the tamping beam or shoe thru a succession of thrust strokes as the machine advances is diagrammatically illustrated in Fig. 10. It will be noted in this diagram that the lift of the heel of the shoe or beam is substantially vertical, while its downward stroke is diagonally forwardly and downwardly, which stroke is followed by a horizontal advance movement coincident with the finished surface of the roadway. The successive forward sliding movements of the shoe or beam at the level of the finished surface overlap each other so that the entire surface is subjected to this final ironing out or troweling effect.

In Figs. 2 and 3 the projecting end of the rack shaft 20 has a hand lever 59 which is used when the machine has advanced forwardly over all of the material that has been deposited on the paving bed and the operator is not satisfied with the quality of its work. He then throws the shaft 20 out of gear by the use of the lever 45. This leaves the shaft 20 entirely free to be operated by the hand lever 59, by depressing the lever 39 to the front he turns the shaft 20, lifts the arms 19, links 18 and the shoe 21. The machine can now be moved backward over the work with the shoe held up. When he has retracted the apparatus as far as necessary, he again throws the shaft 20 into gear and repeats the former work operations, or he can raise the lever 59 which will lower the shoe 21 onto the bed and lock it down by the toggle joints. He can then advance the machine over the work and trowel the surface with the whole weight of the machine holding the shoe down to its work.

At the opposite ends of the tamping beam or shoe 21 are mounted plates 83 extending forwardly of the shoe or tamping beam and closing the ends of the convergent space beneath the beam to retain therein the accumulation of surplus material. Pivotaly mounted upon the ends of the beam or shoe and forming extensions of the retaining end plate 83, are adjustable extensions 84 which can be of any desired shape and which project intermediate the body of concrete and the track rails or side forms 1 in close relationship with the latter, or may be raised above the plane of the deposit when passing obstructions. These adjustable extensions plates serve as spaders, being vibrated up and down with a progressively advancing movement to agitate the concrete material adjacent to the form sides, serving to displace inwardly the coarse aggregates and breaking air pockets, enabling the finer portions of the concrete mixture to settle into close proximity to the guide forms 1, thereby affording a finished marginal surface upon the concrete deposit, which because of the submergence and embodiment of the coarse aggregates and substitution of cement and fine material will afford a stronger union upon the margin and prevent crumbling. The plate 83 and 84 can be removed from the bed of the left hand portion of the sectional shoe 21, and bolted against the left hinge end of the right hand portion of the shoe 21, whenever a short machine is needed.

The tamping beam or shoe 84 shown in Fig. 6 is continuous throughout, its under side being contoured to either parabolic or arcuate form to produce a road surface of predetermined transverse curvature. This shoe or beam 84 is substituted for the beam 21 and is adapted to be bolted directly to the drag links 17. Bosses 85 are provided upon the beam 84 for this purpose. It must be understood that the center hinged sectional shoe 21 which can be adjusted for straight or crowned top surfaces, is only used to surface a straight or prismatic sectioned surface.

It is the present practice in road-building to crown the straightaway portion of the road by elevating the center line above the side margins and to gradually decrease the altitude of such crowns to a flat surface on curves of the road-way. It is for this reason that the elevating and lowering mechanism is provided for the center of the tamping beam or shoe only. It will be understood, however, that the same raising and lowering mechanism provided at the center of the apparatus may be duplicated at either or both ends, in which case one end of the beam or shoe may be raised or lowered to afford an inclined or "banked" surface for curves of the road. In such case the outside margin of the road would be constructed higher than the inside margin. This might be done either

by raising the end of the tamping beam or shoe at the outer side of the curve or by lowering it at the inner side of the curve. If such elevating means is provided at only one end of the beam, such end would be elevated above the intermediate or normal position when traversing the outside of the curve, and would be lowered below such intermediate or normal position when traversing the inside 10 of a road curve.

In Fig. 13 there is illustrated a slightly different form of the tamping means or shoe actuating means, wherein the beam is given a compression stroke throughout substantially its full width instead of the rocking movement before described and the beam or shoe is given a somewhat longer forward sliding movement at the termination of its down stroke. In this construction, the shaft 16' corresponding to the shaft 16 of the previous construction is given a rotary movement and is provided with eccentrics 86, upon which the forward ends of the drag links 17' are mounted. The rear ends of these drag links 25 are connected directly to the rock arm 19' upon the rock shaft 20', without the intermediary of the link 18 previously described. In this construction, the rear end or heel of the shoe or beam is raised and lowered by the 30 oscillation of the arm 19', while at the same time the front end of the beam is raised and lowered by the rotation of the eccentric 86, the shoe or beam being given a forward stroke simultaneously by the action of the 35 eccentric and rock arm, additional to the stroke or movement imparted by the travel of the apparatus. The path of travel of the heel of the beam or shoe in both forward and rearward movement is defined diagrammatically in Fig. 14, showing the movement of point 31 while advancing and while backing.

Figs. 15 to 19^a inclusive illustrate the adaptation of the present road making machine to road-beds of different widths. In 45 Fig. 15, the machine is shown extended by the telescopic extension of the sliding pipe section 7, to accommodate the machine to a road-bed of extreme width. In this figure, the clamping beam or shoe is shown continuous throughout its length, and not sectional or jointed as before described, and furthermore, the shoe corresponds in length with the road-bed. Fig. 16 shows the sliding telescopic frame section retracted for operation 50 upon a road-bed of normal width. In Fig. 17, the machine is shown operating upon a road-bed of less than normal or standard width, in which case, an auxiliary or supplemental form side 90 confining the concrete 60 deposit to the prescribed width while one of the traveling carriages, in this instance, the carriage 5, travels upon a track rail 1, located in spaced relation with the auxiliary form side 90 and beyond the margin of the road-bed. In this case, the traveling beam or shoe

is reduced in thickness through that portion which overhangs the auxiliary form side 90 to afford the necessary clearance, and a special spading blade 84^a is carried upon the tamping beam or shoe at a point coincident with the auxiliary side form 90. For road-beds of less than standard width, the tubular frame section 7 is withdrawn from the outside or second section 6, and inserted into the primary section of the pipe 6 when the 70 narrow machine possesses the same features of adjustability as the wide machine, as shown in Fig. 18. In such case the traveling carriage 5 may ride upon the side form 1, which confines the concrete deposit in lieu 75 of a rail or side form spaced outside the margin of the road-bed as shown in Fig. 17. Figs. 18 and 19^a show the machine applied to narrow pavement or driveway, or half roadway construction, in which one of the pipe 80 sections 6 forming the frame or supporting structure is removed, thus making the standard machine of less width. By employing the single pipe section 6, thus reducing the machine structure to less size, and providing 85 an inwardly spaced form side 92, as shown in Fig. 19, beyond which the reducing extremity of the beam or shoe overhangs in somewhat the same manner as shown in Fig. 17, the machine may be used for making side-walks or 90 comparatively narrow concrete deposits. The machine is thus quite flexible in its 95 adaptation to pavements of different widths and design, being operable with equal facility over a wide range of transverse dimensions. Fig. 19, however, shows a machine of simpler 100 construction, the telescopic feature being omitted, and both carriages 4 and 5 bolted fast to the single pipe 6.

To further insure thorough agitation of the 105 mixture, and to assure uniform coating of all particles with a thin film of cement, and to further break up hard piles and relieve any air pockets which might occur in the deposit, the vibrating shoe 21 has been shown in Fig. 110 20, provided with a series of adjustable agitating fingers or blades. The agitating fingers 93 are provided in a series spaced one from the other, immediately in advance of the upwardly and forwardly inclined compressor shoe 21, but need not be connected directly to the shoe 21. The agitator fingers 93 are carried by a rock shaft 94 mounted in suitable supporting brackets 95, extending 115 forwardly of the compressor shoe 21. They are oscillated into and out of operative position by means of a hand lever 96, engageable in different positions of adjustment with a segment plate 97. The fingers 93 may be straight or plough shaped or right and left 120 twisted, and may be adjusted to an extreme position in which they will project below the grade level as shown by solid lines, or they may be elevated to different degrees, in which 125 they will engage and agitate the accumula- 130

tion of surplus material, before it is acted upon by the compressor shoe or beam 21. The vibratory beam or shoe 21 in its compressive movement, squeezes the material expressing the liquid cement and water, which is progressively forced forwardly thru the accumulation of surplus material. The actions of the agitator fingers 93 stirs and intermixes this accumulation of surplus material and the expressed water and liquid cement, into a fluid mixture of comparatively thin consistency. This insures every particle of the aggregate receiving the thin coating or film of the liquid cement. As the compressor shoe acts upon this mixture the moisture and thin excess cement is again squeezed forwardly to be mixed with further material by the action of the agitator fingers 93. In addition to the agitator fingers 93, there is provided an adjustable gage plate 98, which serves to strike off the excess material, preliminary to its engagement by the compressor shoe 21. This plate 98 may be adjusted vertically to different heights of the established grade level. As the shoe 21 is raised and lowered with its forward thrusting movement, the striking off or gage plate 98 is likewise given a rocking movement, or shovel movement by which the accumulation of excess material is progressively advanced, allowing only so much to pass beneath the lower edge of such striking off and gage plate 98, as can be accommodated beneath the vibrating shoe 21, and compressed below the grade level by the action thereof.

In Fig. 22 there is shown a modification of the operating means for the vibrating tamping beam or shoe. In lieu of the swinging drag bars operated by toggle link connections heretofore described, the pressure shoe or tamping beam 21^a in Fig. 22 is operated by direct pressure in a vertical direction, by means of an eccentric 99 carried upon a revolute shaft 100. This shaft 100 is journalled in hanger arms 101 carried by the main frame of the machine. The eccentric 99 is connected through a dependent arm or strut 102, with the tamping beam or shoe 21^a. The eccentric cam shoe transmits a direct vertical or up and down movement to the shoe. However, to give to the shoe a forward thrust movement, simultaneously with its up and down movement, an oscillating link 103 is pivoted to the hanger arm 101 at one end and to the dependent arm or strut 102 at its opposite end. As the eccentric 99 rotates, it oscillates the arm 102, to and fro in a fore and aft direction about the pivotal connection of such arm 102, with the rocking link 103. This link 103 oscillates about its pivotal connection with the hanger arm 101 to accommodate the vertical movement of the arm 102 as the eccentric reaches the top and bottom of its orbit. The combined oscillatory and vertical movement transmitted to the

shoe 21^a, by the eccentric 99, causes the shoe to describe a path of travel diagrammatically illustrated in Figs. 24, 25 and 26. Attached to the front of the shoe 21^a, is an adjustable gage plate 98, similar to that illustrated in Figs. 20 and 21. This plate may be either continuous as shown in 98^a Fig. 23, or it may be serrated or toothed as shown at 98^b in the same figure. The path of travel of this gauge plate or agitating plate is illustrated in dotted lines in Figs. 26, at 96^c, as though the machine was standing still. However, as the machine advances, as at 96^c, the successive strokes of the gauge plate will overlap each other in the manner diagrammatically illustrated in Fig. 24, performing a shoveling movement. At the rear of the shoe 21^a, there is shown a "slicker" or trowel plate 104, which is given an elliptical path of travel by the combined vertical and oscillatory movements of the shoe. However, as the machine advances, this trowel plate or slicker 104 describes a path of travel such as diagrammatically shown in Fig. 25, wherein it advances in line with the established grade, throughout a part of its stroke, then rises and returns in an elevated position to repeat its advanced troweling stroke in overlapping relation with the previous stroke. However, upon reversal of the direction of travel of the machine, this trowel plate 104, will describe a somewhat different path of travel possessing a climbing over or mixing movement, as shown diagrammatically in Fig. 26, wherein it will be elevated throughout a greater portion of its stroke, and through that portion in which the shoe is depressed, the slicker plate will have a short wiping action on the finished surface. It performs a sliding movement which advances the top material the distance of the stroke of the machine. This is a very valuable mixing movement.

Ordinarily the machine may be operated continuously in a forward direction. However, if to correct inequalities in the finished surface due to unequal distribution of the material and to meet other unusual operating conditions, it is found desirous to rework the surface, the machine may be reversed and driven backward and forward alternately. This movement may be effected with the shoe working or with the shoe held up or down, or up while backing and down while going forward, over the same surface as often as may be found desirable, without interference with the previously deposited and compressed material and without disturbing its finished surface. The motion transmitting mechanism is such that in either of the forms of two operating mechanism described, the shoe during the reverse movement of the machine will have a sliding action and effect its rearward strokes while elevated, and will

contact the road-bed through a very much shorter stroke, but in reverse direction, agreeing with that with which the road-surface was originally finished.

5 As shown in the drawings and heretofore described, the machine will accommodate itself readily to any ordinary curves. However, if it be necessary that the machine negotiate curves of unusually short radii, the 10 front carrying wheel 10^a is unflanged and is of comparatively wide face, so that it may be capable of a greater range of lateral to and fro adjustment relative to the side form for the track rail, while maintaining 15 its engagement therewith. Such use of a plain wheel 10^a of wide tread in lieu of one of the flanged carrying wheels 10 is quite obvious and easily understood. Also the 20 wheels of the carriage 5 can be brought close in a fore and aft direction than is shown in these drawings, or they can be entirely displaced by a single wheel directly under the center of the pipe 7 by splining pipe 7 into pipe 6.

25 From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

35 While in order to comply with the statute, the invention has been described in language more or less specific as to structural features, it is to be understood that the invention is not limited to the specific details shown, but 40 that the means and construction herein disclosed comprises the preferred form of several modes of putting the invention into effect and the invention is, therefore, claimed in any of its forms or modifications within the 45 legitimate and valid scope of the appended claims.

Having thus described my invention, I claim:

1. In a road making machine of the character described, a traveling main frame adapted to span a deposit of concrete material, downwardly and rearwardly inclined drag bars pivoted thereto at their forward ends, a vibratory tamping beam carried by the drag bar having an upwardly and forwardly inclined working face, and means for transmitting to the rear ends of the bars a swinging motion materially below the level of their pivotal connection in unison with the 60 advance of the machine, thereby giving to such beam repeated rocking thrust movement initially in a downwardly and finally in a forwardly direction in which the rear margin of the beam is given a greater range of movement than the front margin of the beam by

which the concrete is subjected to a compacting stroke and then to a smoothing stroke.

2. In a road making machine of the character described, a traveling main frame adapted to span a deposit of concrete material, a beam having an up and down tamping motion carried by the frame and extending transversely across the concrete deposit, mounting for the beam having swinging motion about an axis located materially above the level of the working face of the beam, whereby the beam is given a downwardly and forwardly directed thrust movement about said axis, said beam being inclined upwardly and forwardly and having constantly varying engagement with the deposits of material as the machine moves forwardly to exert camming pressure thereon by which the material is compressed and excess material and moisture squeezed therefrom in a forwardly direction and means for actuating the beam.

3. In a road making machine of the character described, a traveling main frame adapted to span a deposit of concrete or the like, and a strike off beam carried by the main frame extending transversely across the deposit of material and inclined upwardly and forwardly therefrom, affording a convergent recess for excess material collected beneath the beam as the machine advances, a swinging support for the beam, the axis of which is so located above the working surface that the beam engages the road surface at an angle of approximately 45 degrees, a rock arm connected with the free end of the support and approaching substantially dead center relation as the beam reaches the limit of its stroke, the inclined surface of the beam serving to progressively compress the material to grade and expel forwardly the moisture and excess liquid cement into the collected mass in front of the machine and means for transmitting to such beam intermittent forwardly directed tamping thrusts by the oscillation of said rock arm.

4. In a road making machine of the character described, a traveling main frame adapted to span a deposit of concrete or the like, and a strike off beam capable of intermittent downward and forward thrust movement carried by the main frame extending transversely across the deposit of material and inclined upwardly and forwardly therefrom, throughout the forward portion of the beam, a movable support for the beam guiding the beam into engagement with the road surface at an angle of approximately 45 degrees, and toggle link means for actuating the beam, the rearward portion of the beam being extended in approximate parallel relation with the plane of travel of the machine.

5. In a road making machine of the character described, a traveling main frame adapted to span a deposit of concrete or the

like, a tamp beam carried thereby and extending transversely across the deposit, and actuating means for transmitting to said beam, a to and fro motion in a direction downwardly and forwardly inclined to the road bed surface whereby the beam is given an initial downward and forward thrust movement and a subsequent forward substantially horizontal movement substantially in the direction of travel of the machine.

6. In a road making machine of the character described, a traveling main frame adapted to span a deposit of concrete or the like, a flexible vertically vibratory tamp beam carried thereby and extending transversely of the deposit, means for transmitting to the beam a continuous up and down motion, and adjusting means for gradually varying the relative range of motion of different portions of the beam during the progress of the machine to vary the transverse surface contour of the deposit from inclined to flat and vice versa as the machine advances.

7. The herein described process of surfacing concrete road-ways consisting in displacing the excess moisture and liquid cement by intermittent downward and forward angular thrust compression of surplus aggregate above and below the grade line under progressively increasing squeezing pressure by which an excess quantity of the displaced moisture and liquid cement is progressively urged forwardly in the mass preparatory to its compression.

8. In a road making machine of the character described, a traveling main frame, adapted to span a deposit of concrete or the like, a beam carried thereby and extending transversely of the path of travel of the traveling main frame, a rock arm operatively connected with the beam, means for oscillating the rock arm to raise and lower the beam, and guiding means directing the impinging movement of the beam in a forward and downward direction at an acute angle with the surface of the road bed, the rear margin of said beam being contoured to agree with the transverse contour of the finished roadway, the forward margin of the beam being elevated to receive there-beneath a body of surplus material to be compressed as the machine advances.

9. In an apparatus of the character described, two carriages each including a mounting frame and carrying wheels traveling in approximately parallel paths on opposite sides of a deposit of concrete or the like, and an intermediate telescopically adjustable frame by which said carriages are yieldingly connected for movement toward and from each other simultaneously with their advance travel, and concrete treating means carried thereby.

10. In an apparatus of the character described, a traveling main frame formed in

two telescopically adjustable sections for spanning a deposit of concrete or the like, concrete treating means carried thereby, a transverse actuating shaft slidingly mounted upon said frame to compensate for the relative movement of its sections, and carrying wheels operative at opposite sides of the concrete deposit the respective sections of the main frame being automatically adjustable simultaneously with their advance travel to compensate for varying widths of the deposit.

11. In an apparatus of the character described, an expansible and contractible traveling main frame for spanning a deposit of concrete or the like including a pair of independent travelling carriages, a tubular telescopic tie member connecting the carriages for unison travel, and by its telescopic movement enabling the relative adjustment of the carriages to and from each other, guide tracks for said frame, on opposite sides of the concrete deposit, carrying wheels upon said travelling carriages engaging the guide tracks, said frame automatically yielding to compensate for variation in the spacing of the guide tracks in unison with the advance movement of the frame, and concrete treating means carried by said traveling frame.

12. In an apparatus of the character described, a traveling main frame adapted to span a deposit of concrete or the like, carrying wheels at one end of the main frame, an auxiliary travelling frame operatively connected with the opposite end of the main frame, carrying wheels for said auxiliary frame, said main frame and auxiliary frame being adjustable laterally toward and from each other in unison with the advance movement of the main frame to compensate for variations in the width of the deposit operated over, means for effecting the automatic adjustment of said travelling frame, and concrete treating means carried by the main frame.

13. In an apparatus of the character described, a traveling main frame, adapted to span a deposit of concrete or the like, including a pair of traveling carriages telescopically engaged tie sections carried by the respective carriages, said carriages being adjustable laterally toward and from each other in unison with the advance movement of the main frame to compensate for variations in the width of the deposit operated over, carrying wheels for said carriages, guide tracks for said carrying wheels guiding said carriages toward and from each other in accordance with variations of width of the deposit and concrete treating means carried by the main frame.

14. In an apparatus of the character described, two traveling carriages, arranged in parallel spaced relation telescopic tie yielding connecting the carriages one to the other for unison travel but permitting the

carriages to be automatically relatively adjusted one toward the other simultaneously with their advance travel, and concrete treating apparatus carried thereby.

15. In an apparatus of the character described, two traveling carriages arranged in parallel spaced relation, two tubular frame members being telescopically arranged and free for relative longitudinal adjustment by which the carriages are permitted to automatically move toward and from each other in a lateral direction relative to their paths of travel, said adjustment being effected by the advance movement of the carriage, and concrete treating means carried by the apparatus.

16. In an apparatus of the character described, a self propelled traveling main frame adapted to span a deposit of concrete or the like, a vibratory tamping beam arranged transversely of the path of travel, a swinging carrier therefor oscillating about an axis in front of and materially above the level of the working face of the beam, whereby said beam swings through an arc intersecting the surface operated upon at a point inclined approximately 45 degrees from said axis, the thrust of said beam being downwardly and forwardly and rocking beam upon the frame momentarily holding the beam depressed in an approximate condition of rest at the limit of its thrust movement.

17. In an apparatus of the character described, a traveling main frame adapted to span a deposit of concrete or the like, a series of oscillatory drag bars pivotally mounted upon the main frame and extending downwardly and rearwardly therefrom, a tamping beam carried by the lower rear ends of the drag bars, and a rock arm operatively connected with the drag bar and operative toward and from an approximate dead center position for intermittently swinging the bars downwardly and forwardly to thrust the beam against the concrete deposit in an angular direction in relation with the grade line as the apparatus advances.

18. In an apparatus of the character described, a traveling main frame, adapted to span a deposit of concrete or the like, a tamping beam carried by the main frame and arranged transversely of the path of travel, drag bars for said beam extending downwardly and rearwardly and having pivotal connections at their upper and forward end with the main frame, toggle links operatively connected with the tamping beam and means for actuating the toggle links to intermittently thrust the tamping beam downwardly and forwardly in an angular direction in relation with the grade line upon the concrete deposit spanned by the apparatus.

19. In an apparatus of the character described, a traveling main frame, adapted to span a deposit of concrete or the like, a vi-

bratory tamping beam carried by the main frame and arranged transversely of the path of travel, supporting and guiding means therefor, downwardly and rearwardly inclined arms on which the beam is mounted, and means for vertically swinging said arms for transmitting to said beam an alternating up and down movement in which the beam engages the material in a downwardly and forwardly directed thrust movement intersecting the plane of operation at an inclination of approximately 45 degrees.

20. In an apparatus of the character described, a traveling main frame, adapted to span a deposit of concrete or the like, a tamping beam carried by the main frame and arranged transversely of the path of travel, guiding means directing the beam in a forwardly and downwardly inclined direction, and actuating means for transmitting to the beam to and fro motion in such inclined direction and operating to momentarily hold the beam at the limit of its downward thrust movement during a limited advance movement incident to the travel of the apparatus.

21. In an apparatus of the character described, a traveling main frame, adapted to span a deposit of concrete or the like, a tamping beam carried by the main frame and arranged transversely of the path of travel, oscillatory drag bars upon which the beam is supported, a rock shaft and links transmitting motion from the rock shaft to the oscillatory drag bars to effect an up and down swinging movement of the beam additional to the advance movement of the beam incident to the travel of the apparatus.

22. The herein described process of treating concrete deposits consisting in subjecting the deposit to alternating vertical compression strokes and wiping strokes in substantially the plane of the finished surface, such alternating compression and wiping strokes being delivered in overlapping relation.

23. The herein described method of treating concrete deposits consisting in accumulating a surplus of material, adding to the accumulated mass an excess quantity of liquid cement extracted from a portion of the deposit theretofore operated upon, intermittently subjecting such surplus material to progressive compression and subjecting the compressed material to wiping action intermediate successive periods of compression.

24. In an apparatus of the character described, a traveling main frame, adapted to span a deposit of concrete, a tamping beam arranged transversely of the path of travel of the apparatus, said beam having an upwardly and forwardly inclined under surface and to the rear of such inclined surface having an under surface extending in approximate parallel relation with the plane of travel of the apparatus and actuating

mechanism for transmitting to the said beam an alternating up and down movement and for momentarily holding the beam at the limit of its down stroke and effecting an advance movement of the beam while in down position.

25. In an apparatus of the character described, a traveling main frame, adapted to span a deposit of concrete, a tamping beam arranged transversely of the path of travel of the apparatus, and actuating mechanism for transmitting to the beam, alternating downward thrust and retractive motion, the retractive action of said actuating mechanism being momentarily delayed during a limited advance movement of the traveling main frame while the beam is in its down position, thereby affording an advance wiping movement of the beam coincident with the finished surface of the road bed.

26. In an apparatus of the character described, a traveling main frame, adapted to span a deposit of concrete, a tamping beam arranged transversely of the path of travel of the apparatus, said beam having an upwardly and forwardly inclined under surface and a flexible trailing portion disposed rearwardly of the inclined surface in approximate parallel relation with the plane of travel of the apparatus, and means for transmitting to said beam an up and down movement followed by an advance movement while the beam is in down position.

27. In an apparatus of the character described, a traveling main frame, adapted to span a deposit of concrete, a tamping beam arranged transversely of the path of travel of the apparatus, supporting and guiding means for said beam upon which the beam is mounted for up and down swinging motion about an axis of oscillation in advance of the beam and means for actuating the beam into downward and forward thrust engagement with the deposit, and for retracting the beam subsequent to such thrust engagement, said actuating means operating to hold the beam momentarily in its depressed position during a limited advance of the apparatus to effect a wiping action of the beam upon the deposit coincident with the finished surface of the road bed.

28. In an apparatus of the character described, a traveling main frame adapted to span a deposit of concrete or the like, a beam carried thereby and arranged transversely of the path of travel and utilized to strike off all surplus material to predetermined grade and means for transmitting to the beam an up and down swinging motion about a center of oscillation above and in advance of the beam in an angularly disposed path downwardly and forwardly inclined relative to the finished surface of the roadway, the under surface of said beam being inclined upwardly and forwardly in relation with the

plane of the travel and in a plane substantially perpendicular to the downwardly and forwardly inclined path of travel of the beam.

29. In an apparatus of the character described, a traveling main frame adapted to span a deposit of concrete or the like, a beam carried thereby and arranged transversely of the path of travel and utilized to strike off all surplus material to a predetermined grade, said beam having an angularly disposed under surface, the forward portion of which is inclined upwardly and forwardly, the rear portion of which is extended in approximately parallel relation with the plane of travel and means for giving to the beam an alternating up and down motion and for holding the beam momentarily in its depressed position with its rear parallel portion coinciding with the grade line during a limited advance movement of the traveling main frame.

30. In an apparatus of the character described, a traveling main frame adapted to span a deposit of concrete or the like, a beam having a vertical vibratory motion carried thereby and arranged transversely of the path of travel and utilized to strike off surplus material to a predetermined grade, means for actuating the beam, said beam having an angularly disposed under-surface, the forward portion of which is inclined upwardly and forwardly relative to the established level of the finished surface of the deposit, and a flexible trailing rear portion of the beam extended in approximately parallel relation with the plane of travel.

31. The combination with a traveling road making machine, of a strike off beam carried thereby extending transversely of the path of travel of the apparatus, said beam being concave in a longitudinal direction on its under surface and transversely beveled on such under surface and means for changing the longitudinal curvature of said beam simultaneously with the advance travel of the machine.

32. In an apparatus of the character described, a traveling main frame adapted to span a deposit of concrete or the like, a tamping beam carried thereby in transverse relation with the path of travel of the apparatus, means for transmitting to the beam alternating downward thrust and retractive motion, and means for differentially adjusting different portions of the beam to change its contour and thereby vary the transverse contour of the finished surface of said deposit.

33. In an apparatus of the character described, a traveling main frame adapted to span a deposit of concrete or the like, a tamping beam carried thereby in transversely inclined relation with the plane of travel, actuating means for transmitting to such tamping beam alternating downward thrust and retractive movement and adjusting means for

said beam operable during the advance movement of the machine for progressively changing the inclination of the beam to effect a gradual change from flat to an inclined finished road surface and vice versa, during 5 the advance movement of the machine.

34. In an apparatus of the character described, a traveling main frame adapted to span a deposit of concrete or the like, a tamping beam carried thereby in transverse relation with the path of travel, actuating means for transmitting to such tamping beam alternating downward thrust and retractive movement, and adjusting means operable during 10 the travel of the machine for raising and lowering the beam to progressively vary its inclined relation with the plane of operation as the machine progresses.

35. In an apparatus of the character described, a traveling main frame adapted to span a deposit of concrete or the like, a flexible tamping beam carried thereby in transverse relation to the path of travel, actuating means for transmitting to such tamping beam 20 alternating downward thrust and retractive movement, and means for medially flexing the beam to vary the transverse contour of 25 the finished surface of the concrete deposit in unison with the advance travel of the 30 main frame.

36. In an apparatus of the character described, a traveling main frame adapted to span a deposit of concrete or the like, a tamping beam carried thereby in transverse relation to the path of travel, actuating means for transmitting to such tamping beam alternating downward thrust and retractive movement, said beam being medially jointed and 35 means for adjusting the jointed beam to varying angular relations of the connected sections thereof in unison with the advance travel of the main frame.

37. In an apparatus of the character described, a traveling main frame adapted to span a deposit of concrete or the like, a tamping beam carried thereby in transverse relation to the path of travel, actuating means for transmitting to such tamping beam alternating downward thrust and retractive movement, said beam comprising two relatively 45 adjustable sections and means for adjusting said sections while said main frame is in motion to varying inclined relations one with the other to vary the transverse contour of 50 the finished surface of the deposit.

38. In an apparatus of the character described, a traveling main frame adapted to span a deposit of concrete or the like, a gage beam transversely arranged relative to the 60 path of travel, and determining the transverse surface contour of the deposit and vertically disposed vibratory plates at the ends 65 of said beam projecting below the level thereof for acting upon the marginal edges of the deposit and means for transmitting to

the plates continuous up and down motion.

39. In an apparatus of the character described, a traveling main frame adapted to span a deposit of concrete or the like, a gage beam transversely arranged relative to the 70 path of travel, and determining the transverse surface contour of the deposit, and vibratory plates vertically disposed at the ends of said beam and extending below the level of the deposit operated upon for finishing the side margins of the deposit. 75

40. In an apparatus of the character described, a traveling main frame adapted to span a deposit of concrete or the like, a gage beam transversely arranged relative to the 80 path of travel, and determining the transverse surface contour of the deposit, and vertically disposed plates at the ends of said beam and adjustable relative thereto, said plates extending below the level of the deposit operated upon for treating the side 85 margins thereof. 85

41. In an apparatus of the character described, a traveling main frame adapted to span a deposit of concrete or the like, a gage beam transversely arranged relative to the 90 path of travel, and determining the transverse surface contour of the deposit, and vertically disposed plates at the ends of said beam and adjustable relative thereto, said 95 plates extending below the level of the deposit operated upon for treating the side margins thereof, and means for vibrating the beam and plates simultaneously. 95

42. In an apparatus of the character described, a traveling main frame adapted to span a deposit of concrete or the like, a gage beam transversely arranged relative to the 100 path of travel, and determining the transverse surface contour of the deposit, and vertically disposed plates at the ends of said beam and adjustable relative thereto, said plates extending below the level of the deposit operated upon for treating the side margins thereof, said plates and beam being interconnected for unison operation and means 105 for vibrating the beam and plates. 110

43. In an apparatus of the character described, a traveling main frame adapted to span a deposit of concrete or the like, a vibratory gage beam carried thereby in transverse relation to the path of travel, means for transmitting to the beam an alternating up and down motion in a direction downwardly and forwardly inclined relative to the plane of 115 operation, said beam being concave in a direction transversely of the deposit operated upon to afford a transversely convex finished surface, the undersurface of the beam being beveled forwardly and upwardly to afford 120 a camming compression upon an accumulation of surplus material therebeneath. 125

44. In an apparatus of the character described, a traveling main frame adapted to span a deposit of concrete or the like, a vibra- 130

vatory gage beam carried thereby in transverse relation to the path of travel, means for transmitting to the beam an alternating up and down motion in a downwardly and forwardly inclined path of movement, said beam being shaped and alined to agree with the desired transverse contour of the finished surface of the deposit, said beam having its under surface inclined upwardly and forwardly in the direction substantially at right angle to its path of vibratory movement to afford a camming compression upon an accumulation of surplus material thereunder.

45. In an apparatus of the character described, a traveling main frame adapted to span a deposit of concrete or the like, a gage member carried thereby in transverse relation to the path of travel, and elevating means located upon the main frame and extensible 15 during the travelling movement thereof for raising and lowering the center of the gage member independent of the ends thereof to change the transverse contour of the finished surface of the deposit.

20 46. In an apparatus of the character described, a traveling main frame, a gage beam carried thereby in transverse relation to the path of travel, the under surface being of lineal contour, which conforms to the desired 25 transverse contour of the deposit operated upon, a pivotal center upon which the gage beam is mounted for oscillatory movement located above and forwardly of said beam, suspension links supporting the gage beam, 30 rock arms to which said links are connected, and means for actuating the rock arms to elevate and depress the gage beam and at the same time swing it forwardly as it descends.

40 47. In an apparatus of the character described, a traveling main frame, a gage beam carried thereby in transverse relation to the path of travel, the under surface being of lineal contour which conforms to the desired transverse contour of the deposit operated 45 upon, a pivotal center upon which the gage beam is mounted for oscillatory movement located above and forwardly of said beam, toggle links supporting the beam and by their operation serving to raise and lower the beam 50 simultaneously swinging the beam about its pivotal center, said toggle links assuming a substantially dead center position when said beam is depressed, and means for actuating the toggle links.

55 48. In an apparatus of the character described, a traveling main frame, a vibratory gage beam carried thereby in transverse relation to the path of travel for transmitting to the beam an alternating up and down movement, the under surface lineal contour of which conforms to the desired transverse contour of the deposit operated upon, and side plates mounted upon the beam in juxtaposition to the ends thereof and movable to posi-

tions above and below the level of the deposit operated upon.

49. In an apparatus of the character described, a traveling main frame, a gage beam carried thereby in transverse relation with the path of travel, pivoted drag bars for said beam, means for oscillating the drag bars to raise and lower the beam, and means for raising and lowering the beam independent of the drag bars.

70 50. In an apparatus of the character described, a traveling main frame, a gage beam carried thereby in transverse relation with the path of travel, an adjustable carrier for said beam on which the beam is adjustably mounted and actuating means for vibrating the carrier and beam in unison through an alternating up and down movement and additional means for raising and lowering the beam independent of the carrier.

75 51. In an apparatus of the character described, a traveling main frame, a gage beam carried thereby in transverse relation with the path of travel, a pair of rock arms on which the beam is suspended, means for adjusting the rock arms to raise and lower the beam, and means for giving to the beam a vibratory movement independent of the adjustment of the rock arms.

80 52. In an apparatus of the character described, a traveling main frame, a gage beam carried thereby in transverse relation with the path of travel, actuating mechanism imparting to the beam an up and down movement of predetermined extent, and adjusting 85 means for varying the length of such predetermined stroke.

90 53. In an apparatus of the character described, a traveling main frame, a gage beam carried thereby in transverse relation with the path of travel, actuating means for imparting to the beam an up and down movement, and an adjusting means mounted upon the main frame and accessible during the continued operation of the machine for varying 95 the relation of the beam to the horizontal, thereby causing one portion of the beam to operate through its up and down movement at a level different from that in which another portion of the beam effects its up and down movement and thereby progressively changing 100 the inclination of the finished road surface.

105 54. In an apparatus of the character described, a traveling main frame for spanning a deposit of concrete or the like, a gage beam section carried thereby in transverse relation to the path of travel of the apparatus, a swinging mounting for said beam section and adjusting means mounted upon the main 110 frame and accessible during the continued operation of the machine for raising and lowering one end of such beam section to operate at different levels independent of the 115 other end of the beam section and simul- 120

125

130

taneously with the swinging movement of the beam.

55. In an apparatus of the character described, a traveling main frame for spanning a deposit of concrete or the like, a gage beam carried thereby in transverse relation to the path of travel, pivoted drag bars by which said beam is carried, means for oscillating the drag bars to impart an up and down movement to the beam and adjusting means mounted upon the main frame and accessible during the continued operation of the machine for raising and lowering the beam relative to the draw bars to vary the level of operation of said beam and thereby progressively changing the inclination of the finished road surface.

56. In an apparatus of the character described, a traveling main frame for spanning a deposit of concrete or the like, a gage beam carried thereby in transverse relation to the path of travel, pivoted drag bars by which said beam is carried, means for oscillating the drag bars to impart an up and down movement to the beam and means for raising and lowering the beam relative to the draw bars to vary the level of operation of said beam, including a pair of rock arms mounted upon the drag bars and on which the beam is suspended, and means to oscillate the rock arms independent of the oscillation of the drag bars to raise and lower the beam relative to the drag bars and independent of the movement of the drag bars.

57. In an apparatus of the character described, a traveling main frame for spanning a deposit of concrete or the like, a gage beam carried thereby in transverse relation with the path of travel, pivoted drag arms by which the beam is carried, said beam being adjustably connected to said drag bars for movement independent of the drag bars, a rock shaft upon which the drag bars are pivoted, means for rocking said shaft and keeping the shaft in its adjusted position of rocking movement and an operative connection between the rock shaft and beam by which the beam is adjusted relative to the drag bars by the rocking movement of the shaft.

58. In an apparatus of the character described, a traveling main frame for spanning a deposit of concrete or the like, a gage beam carried thereby in transverse relation to the path of travel, means for imparting to said beam a vibratory movement toward and from the deposit, and spading means carried by the vibratory beam extending below the level and immediately in advance thereof, for agitating the material preparatory to operation thereon by the vibrating beam.

59. In an apparatus of the character described, a traveling main frame for spanning a deposit of concrete or the like, a gage

beam carried thereby in transverse relation to the path of travel spading means carried thereby in advance of and extending below the level of the beam and means for giving to such spading means a vibratory digging movement for agitating the material preparatory to operation thereon by the beam.

60. In an apparatus of the character described, a traveling main frame for spanning a deposit of concrete or the like, a gage beam carried thereby in transverse relation to the path of travel, means for imparting to the beam a vibratory movement toward and from the deposit, and spading means carried thereby in advance of and extending below the level of the vibratory beam for agitating the material preparatory to operation thereon by the beam.

61. In an apparatus of the character described, a pair of traveling carriages following guide tracks located on opposite sides of a deposit of concrete or the like, a yielding expansible and contractible intermediate connection between the carriages, enabling automatic adjustment of the carriages toward and from each other simultaneously with their advance movement, auto power mechanism mounted upon one of the carriages, a gage beam determining the transverse contour of the deposit surface carried intermediate said carriages, and yielding power transmission mechanism transmitting driving power from one carriage to the other and adapted to automatically compensate for variations in the relative positions of the carriages due to nonparallel relations of the side forms.

62. In an apparatus of the character described, a pair of traveling carriages following guide tracks located on opposite sides of a deposit of concrete or the like, a freely expansible and contractible intermediate connection between the carriages, enabling automatic adjustment of the travelling carriages toward and from each other simultaneously with their advance movement, auto power mechanism mounted upon one of the carriages, a gage beam determining the transverse contour of the deposit surface carried intermediate said carriages, said carriages being relatively adjustable toward and from each other to automatically compensate for variations in the spacing of the side forms and a compensating driving connection between the carriages by which the carriages are propelled in unison in all positions of relative adjustment.

63. In an apparatus of the character described, a pair of traveling carriages following guide tracks located on opposite sides of a deposit of concrete or the like, a freely expansible and contractible intermediate connection between the travelling carriages, enabling automatic adjustment of the carriages toward and from each other simultaneously

with their advance movement, a gage beam intermediate the carriages operating upon the concrete deposit, and an automatically adjustable transverse connection between said carriages enabling relative adjustment of the carriages toward and from each other to compensate for variations in the spacing of the guide tracks.

64. In an apparatus of the character described, a pair of traveling carriages, a leveling and compacting means carried therebetween and operating upon a concrete deposit, an automatically adjustable transverse connection between said carriages enabling relative adjustment of the carriages toward and from each other simultaneously with their advance movement to compensate for variations in the width of the concrete deposit, an automotive power mechanism mounted on one of the carriages and operatively connected with the other carriage in all positions of relative transverse adjustment.

65. In an apparatus of the character described, a traveling main frame including two spaced carriages traveling on guide rails at opposite sides of a deposit of concrete or the like, a transverse telescopic tie member yieldingly connecting the carriages for unison travel but permitting automatic relative movement toward and from each other simultaneously with their advance movement to automatically compensate for varying spacing of the guide rails, a gage beam carried intermediate the carriages and in transverse relation with the path of travel, means for lengthening and shortening the telescopic tie member independent of its telescopic action to accommodate the apparatus to wide and narrow deposits.

66. In an apparatus of the character described, a traveling main frame including two spaced carriages traveling on guide rails at opposite sides of a deposit of concrete or the like, a transverse telescopic tie member yieldingly connecting the carriages for unison travel but permitting relative movement toward and from each other to automatically compensate for varying spacing of the guide rails, one of the elements of the transverse telescopic tie member being jointed and permitting the insertion and removal of sections to increase and diminish the length of such element without interfering with the telescopic action of the tie member, to accommodate the apparatus to wide and narrow deposits, and a gage means carried intermediate the traveling carriages and extending transversely in relation to the path of travel.

67. In an apparatus of the character described, an expansible and contractible traveling main frame for spanning a deposit of concrete or the like, guide tracks for said frame on opposite sides of the concrete deposit, double flanged carrying wheels engag-

ing the guide tracks, said frame automatically yielding to compensate for variations of the spacing of the guide tracks, to which it is confined by the double flanges of the wheels.

68. In an apparatus of the character described, two traveling carriages arranged in parallel spaced relation and travelling in spaced guide tracks, tubular frame members, telescopically arranged, and free for longitudinal adjustment by which the carriages are permitted to automatically move toward and from each other in a lateral direction relative to their paths of travel in accordance with the variation of spacing of the guide track, simultaneously with their advance movement, and concrete treating means carried by one of the carriages.

69. In an apparatus of the character described a traveling main frame, adapted to span a deposit of concrete or the like, a beam arranged transversely of the path of travel of the apparatus, said beam being provided with a flexible trailing portion disposed rearwardly and means for transmitting to the beam a succession of elongated oval movements in overlapped relation in unison with the travel of the apparatus.

70. In an apparatus of the character described a traveling main frame adapted to span a deposit of concrete or the like, an adjustable gage beam carried thereby, and means for flexing it up and down medially or at the sides, while the apparatus is moving along a paving bed.

71. In an apparatus of the character described, a traveling main frame adapted to span a deposit of concrete or the like, a gage beam carried thereby, and the underside of said beam being shaped to compact a pavement of less width than the capacity of the machine, said beam being of reduced dimension at one end to conform to an auxiliary form laid on the paving bed in parallel spaced relation with the main forms.

72. In an apparatus of the character described, a traveling main frame for spanning a deposit of concrete or the like, a gage beam carried thereby in transverse relation to the path of travel, means for imparting to said beam a movement toward and from the deposit, a series of movable fingers carried by the beam and projecting below the operating face thereof, and means to adjust the fingers for varying depth of operation, said fingers being adjustable to various positions from an inoperative position above the finished plane of the pavement to a range of operation deep into the paving bed.

73. In an apparatus of the character described, a traveling main frame for spanning a deposit of concrete or the like, a gage beam carried thereby in transverse relation to the path of travel, means for imparting to said beam a movement toward and from the deposit, a series of vibrating fingers and

a gage plate in advance of the beam extending below the operating face of the beam, and means to adjust the fingers and the plate relative to the beam for varying heights of operation.

5 74. In an apparatus of the character described a traveling main frame for spanning the deposit of concrete or the like, a gage beam carried thereby in transverse relation to the path of travel, means for imparting to the beam a vibratory movement towards and from the deposit, and spading means extending forwardly thereof, adjacent the ends of the beam and extending below the paving plane to prevent the beam from displacing the material being worked on beyond predetermined side lines.

10 75. In an apparatus of the character described, a traveling main frame for spanning a deposit of concrete or the like, a tamping beam carried thereby in transverse relation to the path of travel and confining means adjacent the ends of the beam to prevent the beam from displacing the material which is 15 being worked on sidewise beyond the predetermined side lines.

In testimony whereof, I have hereunto set my hand this 7th day of May, A. D. 1925.

WILLIAM BAYLEY.
